Specification for Design.

Patented Nov. 1, 1921.

Application filed June 24, 1921. Serial No. 480,242. Term of patent 14 years.

To all whom it may concern:

Be it known that I, LOUIS R. LINSCOTT, a citizen of the United States, residing at Woburn, in the county of Middlesex and State of Massachusetts, have invented a new, original, and ornamental Design for Writing-Paper-Tablet Covers, of which the following is a specification, reference being had

to the accompanying drawing, forming a part thereof.

The figure is a plan view of a writing-paper tablet cover showing my new design.

I claim:

The ornamental design for a writing-paper tablet cover, as shown.

LOUIS R. LINSCOTT.
